UNITED STATES PATENT OFFICE.

CLARK D. PAGE, OF ROCHESTER, NEW YORK.

LIMEKILN.

SPECIFICATION forming part of Letters Patent No. 443,865, dated December 30, 1890.

Application filed June 30, 1890. Serial No. 357,272. (No model.)

To all whom it may concern:

Be it known that I, CLARK D. PAGE, of the city of Rochester, county of Monroe, and State of New York, have invented certain new and useful Improvements in Limekilns; and I do hereby declare the following to be a full, clear, and exact description of the same, reference being had to the accompanying drawings, forming a part of this specification, and to the letters of reference marked thereon.

My present invention relates to limekilns, and has for its object to improve their construction and operation, consisting in certain novelties of construction and combinations of parts, all as will be hereinafter fully described, and the novel features pointed out in the claims at the end of this specification.

In the accompanying drawings, Figure 1 is a vertical section of a kiln constructed in accordance with my invention; Fig. 2, a horizontal section on the line $x-x$ of Fig. 1; Fig. 3, a vertical section on the line $y-y$ of Fig. 2; Fig. 4, a horizontal sectional view on the line $z-z$ of Fig. 1.

Similar letters of reference in the several figures indicate similar parts.

The walls A A of the present limekiln are constructed of masonry in the ordinary manner, and the interior of the cupola is provided with a lining C of fire-brick, as usual. The cupola is made, preferably, of slightly-tapering form, being largest at the furnaces, which latter in the present construction are two in number, (indicated by D D,) arranged on opposite sides and tapering toward the outside. The inner ends of the furnaces are provided with centrally-disposed triangular or wedge-shaped columns or abutments E of fire-brick. The furnaces are preferably formed with grate-openings e in their bottoms, communicating with the ash-pit F; but I propose in my present construction to use a spray of some suitable hydrocarbon instead of coal, and therefore prefer to close this grate-opening with a valve or door E', capable of being opened, when desired, to permit any accumulation of lime in the furnace or combustion-chamber to drop into the ash-pit, from whence it may be removed, when desired, by closing door E', thus preventing an undue quantity of air reaching the furnace during the operation. If desired to dispense with the atom-

izer or spraying devices, the usual grate could be placed in the opening e and solid fuel used in the furnaces.

55

The cupola just below the furnaces is divided into four sections by walls F', supported on arches strong enough to support the charge of lime and unburned stone in the kiln, and the upper sides of these walls are provided with coping-blocks G and G', of fire-brick or other refractory material, connected at the center by a large conical block H, of refractory material, having in its sides recesses, into which the ends of the coping-blocks enter and by which they are held in place. The two blocks G, arranged at right angles to the furnaces, are preferably higher than the others, extending, preferably, above the centers of the furnaces and constituting a partition, preventing the products from passing from one furnace to the other, and also, in connection with the central cone H, forming a solid support for the lime and stone and permitting the flame from the furnace to reach farther in and under it. This bridging and supporting are particularly due to the central cone, which I regard as a very advantageous feature.

Below the furnaces the cupola is enlarged, as at J, to form a cooling and receiving chamber or draw-pit, it being contracted again at the bottom and provided with a partition-wall J', which serves to support to some extent the burned and cooled lime and render the removal easier.

While the kiln, so far described, is adapted for the use of any kind of fuel, I prefer to employ a hydrocarbon-burner of any approved kind and to atomize or spray it into the combustion-chamber by a steam-atomizer. In the drawings, the letter K designates a suitable atomizer arranged within each of the furnaces adapted to project a burning spray of oil and steam mixed with a suitable quantity of air to support combustion against the wedge-shaped abutments E, which will cause it to divide and entering the cupola burn the fuel and limestone therein contained, the copings G and G' preventing the flames from one entering the other furnace and directing them upward.

The boiler L for generating the steam operating the atomizers or machinery, if de-

sired, I prefer to locate within the cupola below the furnaces, as shown, and in such position that while it will not be subjected to the weight of the contents of the kiln it will be subjected to the action of the white-hot lime below the furnaces and supporting-arches, and thus the heat given off while the lime is cooling will be utilized. This manner of locating the boiler in position to be heated by the lime coming from the hottest part of the kiln effects a saving in fuel and is a vast improvement over locating it where a portion of the direct heat from the furnaces is taken to heat the boiler. As the boiler extends transversely through the cupola, I prefer to extend the steam-pipes m from opposite ends thereof to the respective atomizers, though any other arrangement could as well be had—as, for instance, if a greater number of furnaces or atomizers are employed the water is supplied to the boiler through pipe n and the oil to the atomizers by pipe o .

Suitable apertures p are provided opening into the cupola for the insertion of bars or pokers with which to knock the accumulations of lime from the arches or boiler and to bring the lime down should there be a tendency to bridge.

The manner of charging and burning kilns of this class is so well understood by those skilled in the art that no further description is deemed necessary.

I claim as my invention—

1. In a limekiln, the combination, with the cupola, of a combustion-chamber having a wedge-shaped abutment in its discharge end

and a hydrocarbon-atomizer discharging against the edge of said abutment, substantially as described.

2. In a limekiln, the combination, with the cupola, of a combustion-chamber having a hydrocarbon-atomizer therein, a discharge-opening in its lower side, and a door or valve for closing said aperture, adapted to be opened when desired, substantially as described. 45

3. In a limekiln, the combination, with the cupola and the furnaces at the sides thereof, of a steam-boiler within the cupola, located below said furnaces and heated by the burned lime, hydrocarbon-atomizers located in the furnaces and discharging laterally in the cupola, and connections between the boiler and atomizers for conveying steam to the latter, substantially as described.

4. In a limekiln, the combination, with the cupola, of the furnaces, the division-walls having coping-blocks $G G'$, the former being the higher and arranged at an angle to the furnace-opening, and the central cone H of refractory material, extending above the furnace-opening, substantially as described. 55

5. In a limekiln, the combination, with the cupola and furnace, of a transverse division wall or arch extending below the furnace, and a steam-boiler extending transversely of the cupola beneath the arch, substantially as described. 65
